United States Patent Office.

JOSEPH P. WHITE, OF SAVANNAH, GEORGIA.

Letters Patent No. 95,058, dated September 21, 1869.

IMPROVEMENT IN COMBINATION-LOCKS.

The Schedule referred to in these Letters Patent and making part of the same.

To all whom it may concern:

Be it known that I, JOSEPH P. WHITE, of Savannah, in the county of Chatham, and State of Georgia, have invented a new and improved Combination-Lock; and I do hereby declare that the following is a full, clear, and exact description thereof, which will enable others skilled in the art to make and use the same, reference being had to the accompanying drawing, forming part of this specification.

This invention relates to improvements in combination-locks, having for its object to provide a simple and cheap lock capable of a great number of combinations.

It consists in a series of vibrating tumblers, notched at the ends, for the reception of a lug on the bolt when sliding back for unlocking, which are provided with auxiliary tumblers, to be acted on by a series of rotating eccentric disks, worked by the key to move the said tumblers for bringing the notches therein to the position coinciding with the lug on the bolt, to allow it to be retracted.

These auxiliary tumblers are engaged with the others by spring-dogs, when the bolt is in the locked condition, and the whole are suspended on the cam-wheels, so that the notches do not coincide with the lug on the bolt, thereby preventing its withdrawal.

When the bolt is withdrawn into the notches of the tumblers, it disengages the ends of the auxiliary tumblers from the spring-dogs, by which they are connected to the main tumblers.

These auxiliary tumblers then rest on the edges of the eccentric wheels, and the latter are then adjusted for any desired combination, which may be determined by an indicator-scale around the key-hole.

On throwing the bolt forward for locking, the auxiliary tumblers will be so engaged at the moment of the escape of the lug from the notches of the tumblers, with the aforesaid spring-dogs, that for unlocking, the eccentric wheels must be brought to the same position they occupied when locking, in order that the notches of the tumblers (which are then suspended on the eccentric wheels, through the medium of the auxiliary tumblers,) will coincide with the lug.

Figure 1 represents a rear view of my improved lock, with the back of the case removed.

Figure 2 represents a longitudinal section, taken on the line $x-x$ of fig. 1.

Figure 3 represents a plan view of one of the auxiliary tumblers.

Figure 4 represents a plan view of one of the main tumblers.

Figure 5 represents a front view of the indicator-dial.

Figure 6 represents a side view of the eccentric disks.

Figure 7 represents one of the eccentric disks. Similar letters of reference indicate corresponding parts.

A represents the bolt, having a broad flat extension, A', slotted at B, to slide back and forth on the stud B'.

It is also provided at the rear and behind the extension A' with a lug, C, clearly shown in dotted lines in fig. 1.

A series of three or more tumblers, D, is pivoted on the said stud B', with its free ends having notches, D', extending to the bolt A. These notches are to receive the lug C of the bolt when it is retracted.

E represents a series of auxiliary tumblers, equal in number to the tumblers D, and also pivoted to the bolt B'. They are shorter than the tumblers D, but project in the same direction, and have projections, E', to be acted on by the cam-wheels F.

They are arranged alternately with the main tumblers D, as clearly shown in the section fig. 2.

The latter have, at their free ends, right-angled spring-dogs, D'', so pivoted to their faces that the short arms D'', which are suitably curved on the sides, will be forced by the springs D', to some extent, into the path of the lug C, when entering the notches D'.

The long arms of these dogs are provided with studs, D'', for engaging with the notched ends of the auxiliary tumblers E, when not disengaged by the lug C wedging into the notches D', against the short arms D''.

The eccentric disks F are pivoted on the spindle F¹ of the key, and arranged opposite the projections E' of the auxiliary tumblers E, one disk for each tumbler.

The cam-teeth or projections on the said disks may be made in any preferred order. The disks are loose on the spindle, and the latter is provided with an arm, F², projecting from the inner end, and having a stud, F³, for engaging a hole in the face of the innermost disk to turn it.

The central disk is turned by the first through a connection formed by studs F⁴ projecting from their adjacent faces, and the other disk is similarly moved by the middle one. In this way each disk may be moved by the key, and adjusted to any required position.

The indicator-scale G, around the key on the front of the lock, is designed to have as many numbers as there are projections on the cam-wheels.

H represents the dog for locking the bolt, and

I represents springs, for bearing on the upper edges of the auxiliary tumblers at K, for pressing them down on the cam-wheels.

When the bolt is unlocked, the spring-dogs are thrown out of connection with the notched ends of the auxiliary tumblers, as previously stated, leaving the latter free to be moved by the cam-wheels to per-

mit the latter to be set for any desired combination, which is done as follows:

The combination being determined upon, say 1—4—6, the key is drawn outward so as to press the stud F³ against the face of the cam-disk a. It is then turned to the right, till the stud falls into the hole. The turning is then continued two revolutions, and enough more to bring the mark L of the disk L', which turns with the key, opposite to figure 6. This sets the disk d. The turning is then reversed one revolution, and continued till the mark L is opposite figure 4. This sets disk b. Again the turning is reversed, and the mark L brought to figure 1, setting the disk a. The key is then pushed forward to disengage the stud from the hole in the disk a, when it is in position to act on the dog H, and the extension A' of the bolt for locking it. When it is so locked, the auxiliary tumblers E, resting on the cams as set by the combination used as above stated, will be connected to the main tumblers D by the spring-dog, and this connection will be such that

the cams must stand in precisely the same position when it is required to retract the bolt, or all the notches will not be in the right position to receive the lug C.

If it is not required to use all the cam-disks in making up a combination, only one or two may be used, the others not being disturbed.

Having thus described my invention,

What I claim as new, and desire to secure by Letters Patent, is—

1. The tumblers D, auxiliary tumblers E, spring-dogs D², and bolt A, arranged substantially as specified.
2. The combination of the tumblers D, auxiliary tumblers E, and eccentric disks F, substantially as specified.
